UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

AUTOMATIC PEDAL-FOLDER FOR PLAYER-PIANOS AND THE LIKE.

1,077,499.

Specification of Letters Patent.

Patented Nov. 4, 1913.

Application filed November 14, 1912. Serial No. 731,383.

To all whom it may concern:

Be it known that I, FRANK C. WHITE, a citizen of the United States, residing at Meriden, New Haven county, State of Connecticut, have invented certain new and useful Improvements in Automatic Pedal-Folders for Player-Pianos and the like, of which the following is a full, clear, and exact description.

10 My invention relates to improvements in player mechanisms for pianos and the like.

This invention relates more particularly to means for automatically controlling the pumping pedals whereby when the instrument is ready for playing, the pedals will drop down from a folded to the operative position, and when the instrument is closed up or restored to a position where the instrument is to be played manually, the said 15 pumping pedals will be automatically folded into the casing out of the way.

20 In the drawings, Figure 1 is a diagrammatic illustration of certain parts of a keyboard instrument equipped with a mechanical player and showing such parts as are 25 essential to a full understanding of my invention. Fig. 2 is a detail view.

25 In the drawings, 1 represents the lower front panel of a piano casing suitably cut 30 away so that the pedals described may be folded into said space.

2 represents the key bed.

3 represents an ordinary piano key.

4 represents a foot pedal or pumping 35 pedal, two usually being provided.

5 represents a support for the pumping pedal, the same being pivoted at 6 and arranged to swing down into the operative or extended position indicated in the drawings, or folded up to a vertical or retired position wherein the foot pedal 4 is housed from view within the piano casing.

7 is the usual equalizer bellows having a movable backboard 8. This equalizer bellows is distended by means of a spring 9 and is collapsed by means of a suitable exhauster bellows 7^a which is suitably connected with the foot pedal 4 by well known linkage, conventionally shown. In the present instance, the equalizer bellows is utilized for holding up the foot pedal and its support, the expanding movement of said equalizer bellows being employed for this act as hereinafter described.

10 is a counterbalancing spring which 55 at one end suitably engages with an appropriate bracket 11 on the support 5, and at the other end is held by an adjustable abutment 12. In the form shown, this spring 10 has an intermediate coil which surrounds a support 13. The function of this spring 10 is simply to carry part of the weight of the support 5 and foot pedal 4 when said pedal is down in its operative position, thus making it easy to start the 60 same on its folding movement. The means for folding up the foot pedal and its support comprises a lever 14 pivotally mounted at 15 and connected by a link 16 with a lever 17 pivoted at 18 and carrying a hook 70 link 19.

20 is a hook at the end of the link 19 which operates as a latch and is arranged to engage a latch pin 21 carried by the movable backboard 8 of the equalizer bellows 7.

When the parts are in position for mechanical playing, the foot pedal and the other parts assume the position shown in the drawings in which the latch link 19 is 80 lifted so that as the backboard 8 of the equalizer bellows moves to and fro during the operation of the instrument, the pin 21 will not engage the hook. When, however, the hook 20 engages the pin, the outward movement of the backboard 8 will cause the lever 17 to swing and will, through the medium of link 16 and lever 14, swing the pedal support and the pedal 4 up to the vertical position. When the 90 instrument is being played mechanically, the latch link 19 is held elevated by means of a trip wire 22 connected to a lever 23 pivoted at 24. One arm of this lever 23 is suitably connected with a link 25, which in 95 turn is connected with a movable key slip 26, which, when open, will move the lever 23 to such a position as to lift the latch trip 22 so that said hook 20 cannot engage the latch pin 21. When, however, the key slip 100 26 is shifted to cover the customary controlling devices, one of which is indicated at 26^a, this act of shifting the key slip will result in the dropping of the latch link 19 to a position where it can engage the latch 105 pin 21. If the operator now continues for a moment to pump on the pedal 4 to a degree sufficient to collapse the equalizer bel-

lows, the backboard 8 will be drawn in until its latch pin engages the hook 20. As soon as the pumping on the pedal 4 ceases, the backboard 8 of the equalizer bellows 5 will move out as the bellows is distended by the spring 9, which movement will, through the medium of the levers heretofore described, swing the pedal support 5 and pedal 4 up into the folded position.

27 is a relief valve suitably associated with the exhauster bellows and by which a free vent may be given to the exhauster bellows when it is performing the function of folding up the pedals, thereby facilitating that 10 act and making it move quickly. This relief valve 27 is opened by means of a bell-crank lever 28, which latter is suitably connected with the lever 17 as by means of a link 29. As will be seen from the drawings, 15 when the lever 17 moves in a direction to fold up the pedal 4, this movement will, through the medium of link 29, instantly open the relief valve 27, allowing air to freely flow into the equalizer bellows so as 20 to give the spring 9 free play.

While it is important to provide means for mechanically or automatically folding up the foot pedals, it is also very desirable to provide means whereby the foot pedals may 25 be extended or opened to the operative position, which act is controllable by the mere act of preparing the instrument ready for mechanical playing, hence I utilize one of the usual and easily accessible parts of the 30 player, in this instance the key slip 26, as the controlling element. To that end I provide means whereby the mere act of moving the key slip 26 from its closed to its open 35 position shown in the drawings, will release the foot pedals 4 and the support 5 and swing them outwardly so that they may descend by gravity to the open operative position. This means comprises a connection 40 between the key slip 26 and the lever 14. 45 This connection in its preferred form comprises a pedal trip rod 30 connected at one end to the lever 23 and at its other end to the link 16. In this particular instance, the link 16 is provided with an offset arm 31 50 through the end of which the trip rod 30 slides. The rod 30 is provided with an adjustable button or abutment 32 so that when the latter is lifted by the opening movement of the key slip 26, it will engage the arm 31 55 and lift the link 16, in turn swinging the lever 14 in an outward direction to start the pedal 4 and the support 5 from its folded position toward its open or operative position to which it may descend by gravity, being cushioned in its descent by the 60 balance spring 10. From the foregoing it will be seen that not only is an automatic mechanical power device employed for folding the pedals when it is not desired to play

the instrument mechanically, but I also 65 provide means for automatically releasing and unfolding said pumping pedals by the mere act of opening the key slip, this being, as I believe, the handiest of the various instrumentalities which are easily accessible 70 which may be said to constitute part of the mechanical player apparatus as distinguished from ordinary piano parts.

While I have described my invention in a preferred form in which I have employed 75 one of the regular mechanical parts of the mechanical player mechanism as the power or self-acting means for shifting the foot pedal from either of its two positions toward its other position, and also have employed one of the regular parts of the player mechanism as the manually controlled device for determining the moment of operation of said self-acting means, it is obvious 80 that the invention should not be thus limited 85 in its broadest aspect, it being, as I believe, broadly new to provide in an instrument of this character means which is capable of imparting both a folding movement to the pedals as well as an unfolding movement 90 thereto to thereby guarantee the positive and certain folding up of the pedals when the instrument is to be closed or put in condition for manual playing, and to also guarantee the certain swinging down of the foot 95 pedals to the extended or operative position when the instrument is to be played mechanically and the key slip 20 is open.

What I claim is:

1. In a pneumatic player apparatus, movable pumping pedal mechanism having an extended position and a retired position, power controlled means to move said pedal mechanism from the extended to the retired position, and manually controllable means 100 coöperating therewith for starting said pedal mechanism on its movement from its retired toward its extended position.

2. In a pneumatic player apparatus, movable pumping pedal mechanism having an 110 extended position and a retired position, power controlled means to move said pedal mechanism from the extended to the retired position, and manually controllable means for starting said pedal mechanism on its 115 movement from its retired toward its extended position, said manually controllable means coöperating with said power mechanism to couple and uncouple the latter with said pedal mechanism.

3. In a player piano, movable pumping pedal mechanism having an extended position and a retired position, power controlled means to move said pedal mechanism from the extended to the retired position, and manually 125 controllable means for starting said pedal mechanism on its movement from its retired toward its extended position, said manually

- controllable means coöperating with said power mechanism to couple and uncouple the latter with said pedal mechanism, said manually controllable means comprising a 5 movable key slip.
4. In an apparatus of the character described for mechanical player mechanism, a foldable foot pedal pumping mechanism, a collapsible bellows, a spring for normally 10 distending said bellows, a connection between the movable part of said bellows and said pumping pedal mechanism to fold up said pumping pedal mechanism by the distention of said bellows, a relief valve connected with said bellows, with means for opening said valve when said bellows is being distended for the purpose of folding said pumping pedal mechanism.
5. In a musical instrument, the combination 15 of pumping pedal mechanism movable into and from operative position, including a collapsible bellows arranged to move said pedals positively into the inoperative position, and a relief valve for said bellows to permit the same to operate freely when 20 performing said work.
6. In a keyboard musical instrument, the combination of pumping pedal mechanism movable into and from operative position, including a collapsible bellows arranged to move said pedals positively into the inoperative 25 position, a relief valve for said bellows to permit the same to operate freely when performing said work, a pneumatic means for putting said bellows in condition to move said pedals to said inoperative position, and a manually controllable means adjacent to the keyboard for opening said relief valve.
7. In a pneumatic player apparatus, in combination with a movable pumping pedal 30 mechanism having an extended position and a retired position, power controlled means to move said pedal mechanism from the extended to the retired position, and means co-operating therewith for starting said pedal 35 mechanism on its movement from its retired toward its extended position.
